UNITED STATES PATENT OFFICE.

CLARK C. WHITE, OF DELHI, IOWA.

CHICKEN-BROODER COOP.

Application filed August 17, 1922. Serial No. 582,514.

To all whom it may concern:

Be it known that I, CLARK C. WHITE, a citizen of the United States of America, and a resident of Delhi, in the county of 5 Delaware and State of Iowa, have invented a new and Improved Chicken-Brooder Coop, of which the following is a description.

The general object of my invention is to provide a novel chicken brooder coop so constructed and arranged as to keep the chickens free from the stamping of an uneasy hen when the chicks are shut in as in early morning or before the chicks are let out for the day or on a rainy day. It is also mite proof and 15 proof against the attacks of small animals.

The nature of the invention and its distinctive features and advantages will clearly appear as the description proceeds.

Reference is to be had to the accompanying drawings forming a part of this specification, it being understood that the drawings are merely illustrative of one example of the invention.

Figure 1 is a front elevation of a brooder coop embodying my invention;

Figure 2 is a transverse vertical section on the line 2—2, Figure 1;

Figure 3 is a longitudinal vertical section on the line 3—3, Figure 2;

Figure 4 is a sectional plan view, the section being taken on the line 4—4, Figure 2.

In constructing a brooder coop in accordance with the illustrated example I form the same of sheet metal. The numeral 10 indicates the bottom plates; 11, the back; 12, the front formed of a frame having side posts and intermediate posts 13, the front being provided with wire mesh 14 between two of the upright posts, the space between the 40 other upright posts being open and closed by a screen door 17 sliding in an upper channel 15 on the front 12 and a bottom channel bar 16.

The numeral 18 indicates front and back plates of the pitch roof of the coop, the said plates 18 being locked to the back 11 and the front 12 as follows: The front 12 has at the upper edge thereof a narrow oblique flange 19 directed outwardly and downwardly on which the adjacent roof plate 18 rests, said roof plate on its lower edge being returned inwardly as at 20 to engage the flange 19. Similarly, the back 11 along the top edge thereof has an outwardly directed oblique flange 21 on which the rear roof plate 18 rests and said roof plate has

its lower edge turned downwardly as at 22 to hook under said flange 21. The adjacent edges of the back and front roof plates 18 have reverse oblique flanges 23 at the peak 60 of the roof and said flanges 23 are engaged by a dovetail ridge bar 24.

An important feature of my invention is the provision of a vertical partition 25 adjacent the plane of ridge bar 24. Said partition 25 includes a bottom bar 26 having a channel form at the under side to receive a raised rib 27 on the bottom 10. The upper side of the bar 26 has side flanges 28, 29 giving said upper side of the bar a channel 70 form to slidably receive the bottom rail 30 of a door 31 forming a closure for an opening in said partition 25. At the top the door 31 is slidable in a channel 32 formed by side plates 33 on a horizontal bar 34 secured to and forming part of the partition 25. Said partition 25 has a top bar 35 directly below the ridge bar 24. At opposite sides of partition 25 are angle brackets 36 riveted to the sides 42 of the coop and holding 80 said partition.

The bottom 10 at the back edge is turned downward obliquely as at 38 to have hooked engagement with the upturned edge 37 at the lower edge of the back 11. Similarly, 85 at the front edge of the bottom 10, the same is formed with a downturned oblique edge 48 beneath which is engaged the upturned edge flange 39 on the front 12.

The lower edges 41 of the sides 42 are 90 upturned at the inner sides and engaged by the downturned oblique edges 43 on the bottom 10 at the sides. The connection between the sides 42 and the back and front of the coop is similar to the connection of the bottom with the back and front, said sides having at the front edges thereof oblique flanges 44 directed laterally inward and engaging the bent vertical side edges 45 on the front 12. Similarly, at the rear edges of the side 100 plates 42, said plates have oblique flanges 46 directed laterally inward and engaging bent edges 47 on the back 11.

The described construction permits of the parts of the coop being assembled in knock-down form and facilitates the assemblage of the parts in erect form. The described engagement of the edges of the front, back, sides, bottom and roof permits of the sliding movements of the parts or a hooking engagement. Similarly, the partition 25 may be readily positioned and capable of sliding on

the bottom rib 27 or said partition may be dropped into place.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. In a structure of the class described enclosing walls, a roof, a bottom having a rib thereon at the upper surface, and a removable partition presenting a channel at the lower edge thereof receiving said rib.

2. A structure of the class described including a front, back, sides, roof and a bottom having a rib thereon at the upper surface, a removable partition presenting a channel at the lower edge thereof receiving said rib, together with members on said sides engaging said partition at opposite sides near the top thereof.

3. A structure of the class described including a bottom having a rib projecting above the surface of said bottom, a removable partition formed with means at its

lower edge to accommodate said rib, means on the sides of the structure to hold the upper end of said partition in place, a door on said partition, and upper and lower horizontal guides on said partition in which guides said door is slidable.

4. A knock-down structure of the character described, including a front, a back, sides, bottom and roof, the edges of which present turned-over flanges for engaging with the flanges of the adjacent members, the bottom of said structure being in addition formed with a longitudinally extending rib projecting above the upper face thereof, a pair of uprights extending between said bottom and said roof and secured to the sides of the structure, a channel member extending between said uprights adjacent the top, a second channel member at the bottom ends of said uprights fastening the latter ends of the uprights to said rib, division elements extending between the bottom and the roof along one side of said channel members for dividing said structure into two compartments, a sliding door interposed between the two channel members for communicating one compartment with the other.

CLARK C. WHITE.
